(57) **CLAIM**

The ornamental design for a lubricant pump as shown and described.

DESCRIPTION

FIG. 1 is a right front isometric view of a lubricant pump according to the present invention.

FIG. 2 is a left front isometric view of the lubricant pump of FIG. 1; and,

FIG. 3 is a front elevation view of the lubricant pump of FIG. 1.

Portions of the article shown in broken lines form no part of the claimed design.

1 Claim, 3 Drawing Sheets
